HAIR WAVING APPARATUS

Ragnvald G. Leland, New York, N. Y.

Application August 13, 1937, Serial No. 158,985

8 Claims. (Cl. 132—33)

This invention relates to hair waving apparatus.

An object of the invention is to provide mechanism which rapidly winds a strand of hair on a forming bar and insures a uniform tension on the hair without discomfort to the person operated upon.

The device includes a clip member adapted to receive a strand of hair and properly position the same around the bar and guide the strand of hair in its winding operation. It also includes the clip turning apparatus which receives the bar which is removably coupled to the clip member and includes a screw with a clutch member thereon adapted to be reciprocated on the screw and rapidly turn the screw and the clip member when the clutch is reciprocated on the screw. More specifically the operation of the clutch member causes the screw to turn only when the clutch member is moved outwardly on the screw thus exerting no pressure on the head when the device is being turned.

My improved apparatus embodies many novel features of construction and combinations and arrangements of parts, all of which will be more fully hereinafter described and pointed out in the claims.

In the accompanying drawing—

Fig. 1 is a view in sectional elevation illustrating my improved apparatus in operative position;

Fig. 2 is an enlarged plan view of the base member showing the forming bar in section and clamped therein;

Fig. 3 is a fragmentary view in elevation showing the parts in position for winding the hair on the forming bar;

Fig. 4 is a view in elevation of the outer end of the forming bar showing the clip member in section thereon;

Fig. 5 is a perspective view of the lower end of the sleeve which forms a part of the hair winding apparatus.

The reference character A is employed to indicate generally a base member which is adapted to be located close to the scalp and clamp a forming bar 10 therein with a strand of hair 11 clamped against the forming bar. This base member A is provided with an upper or outer plate 12 having a notch 13 therein.

The parts above described are disclosed in my Patent No. 2,075,652 granted March 30, 1937, and constitute no part of the present invention excepting that said base member cooperates to a certain extent with the hair turning apparatus, as will be more fully hereinafter explained.

The hair turning apparatus includes a clip member indicated generally by the reference character B which constitutes a collar 14 mounted to slide freely on the forming bar 10 and provided with a pair of spring arms 15 and 16 located substantially parallel to the forming bar but spaced therefrom and adapted to receive a strand of hair under the same and hold the said hair with sufficient firmness in its curled or wound position around the forming bar. Both of these spring arms 15 and 16 have outwardly flared lower ends 17 and 18 respectively, and the arm 16 is preferably longer than the arm 15 so that when the clip member is in its initial position the lower end of the arm 16 will rest in the notch 13 of base A and hold the clip member against turning movement, but it is understood that this engagement in the notch is merely a temporary one due to the fact that the lower extremity of the arm 16 is beveled or tapered as shown at 19 so as to permit the arm 16 to ride out of the notch when turned in the proper direction.

The reference character C is employed to indicate generally a clip turning member and includes a sleeve 20 adapted to slide freely on the forming bar. This sleeve 20 at its lower end is formed with a notch or recess 21 of general bayonet form to receive an angular finger 22 on the end of the clip member B so as to couple the sleeve to the clip member.

It will be noted particularly by reference to Fig. 4 of the drawing that the upper or outer end of the forming bar 10 is enlarged as shown at 23 so as to prevent the clip member from being removed entirely from the bar.

A screw 24 is fixedly secured at its lower end to the sleeve 20 and is provided at its outer end with a cap 25 which is swiveled on to the enlarged outer end 26 of the screw, and roller bearings 27 are provided between the cap and the enlarged end of the screw so as to reduce friction to a minimum.

The reference character D is employed to indicate generally a ball clutch member which slides freely on the screw 24. This ball clutch member includes an outer sleeve 28 in which shorter sleeves 29 and 30 are rigidly secured and spaced apart leaving an annular space 31 between them. The sleeve 30 which constitutes the lower sleeve is formed with notches 33 to receive therein a ball 34 so that when the clutch member is moved outwardly this ball is held against movement in one of the notches 33 and imparts a rotary motion to the screw 24, but when the clutch member is moved inwardly or downwardly the ball 34 is moved inwardly or downwardly the ball 34

rides out of the notch 33 and turns freely in the space 31 so that it does not impart rotary motion to the screw.

A pair of finger receiving arms 35 are secured 5 to the clutch member D so that when the operator grasps these arms with two fingers of his hand and positions another finger of his hand on the cap 25 he can impart a reciprocating motion to the clutch member to rapidly revolve the hair 10 winding apparatus.

The sleeve 20 of the hair winding apparatus is provided with a wire clamp 36 through which the end of the strand of hair 11 may be positioned and may be, in accordance with the length of 15 said strand, inserted through the clamp one or more times.

The operation of the apparatus is as follows: The strand of hair 11 and the forming bar 10 are clamped in the base member A with the latter close to the scalp of the head, and the clip member B is then moved down the bar 10 so as to position its spring arms 15 and 16 over the strand of hair after the latter has been given at least a half turn around the forming bar, and 25 the longer spring arm 16 is located in the notch 13 of the base member A.

Any desired number of these base members and forming bars with their clip members may be positioned on the head of the person operated 30 upon as it is obvious that only one of the hair turning apparatuses indicated generally by the reference character C is necessary to wind the clip members and strands of hair on any desired number of forming bars, thus the operator can 35 rapidly move the clip winding apparatus from one forming bar to the other and quickly and uniformly wind the strands of hair on the forming bar.

When the hair winding apparatus is in position 40 on the forming bar its notch or recess 21 will receive the finger 22 and couple the clip member B to the sleeve 20. The operator then, as above explained, imparts as many reciprocating motions to the clutch member D as may be necessary to rapidly and uniformly wind the hair on 45 the forming bar. This apparatus is then removed from the clutch member and is positioned on the next forming bar, and it will of course be noted that when the hair is wound on the forming bar the clip member B will hold the hair wound thereon in position to receive the next treatment to which the hair is subjected.

While I have illustrated and described what I believe to be the preferred embodiment of my 55 invention, it is obvious that various changes might be made in the general form and arrangement of parts without departing from the invention, hence I do not limit myself to the specific details set forth but consider myself at 60 liberty to make such changes and alterations as fairly fall within the spirit and scope of the appended claims.

I claim:

1. A hair waving apparatus including a forming bar, a clip member on the forming bar adapted to hold a strand of hair wound thereon and guide the strand of hair in the winding operation, said clip member being movable on the forming bar and including a collar and a pair 65 of spring arms depending from the collar, a clip turning member including a sleeve adapted to receive the forming bar, means separably coupling the clip member and the sleeve, a screw fixed in the sleeve, and a ball clutch member adapted to be reciprocated on the screw to im- 70

part rotary motion to the same and to the sleeve and clip when the clutch member is moved outwardly from the screw.

2. A hair waving apparatus including a forming bar, a clip member on the forming bar adapted to hold a strand of hair wound thereon and guide the strand of hair in the winding operation, said clip member being movable on the forming bar and including a collar and a pair of spring arms depending from the collar, a clip turning member including a sleeve adapted to receive the forming bar, means separably coupling the clip member and the sleeve, a screw fixed in the sleeve, and a ball clutch member adapted to be reciprocated on the screw to impart rotary motion to the same and to the sleeve and clip when the clutch member is moved outwardly from the screw, a cap swiveled to the outer end of the screw and finger receiving arms 10 on the clutch member. 15

3. A hair waving apparatus including a forming bar, a clip member on the forming bar adapted to hold a strand of hair wound thereon and guide the strand of hair in the winding operation, a clip turning member including a sleeve adapted to receive the forming bar, means separably coupling the clip member and the sleeve, a screw fixed in the sleeve, and a ball clutch member adapted to be reciprocated on the screw to impart rotary motion to the same 20 and to the sleeve and clip when the clutch member is moved outwardly from the screw, and a clamp on the sleeve adapted to receive a strand 25 of hair therein.

4. A hair waving apparatus including a forming bar, a clip member on the forming bar adapted to hold a strand of hair wound thereon and guide the strand of hair in the winding operation, a clip turning member including a sleeve adapted to receive the forming bar, means separably coupling the clip member and the sleeve, a screw fixed in the sleeve, and a ball clutch member adapted to be reciprocated on the screw to impart rotary motion to the same and to the sleeve and clip when the clutch member 40 is moved outwardly from the screw, said coupling means including a finger on the clip member and a notch in the end of the sleeve receiving 45 the same.

5. A hair waving apparatus including a forming bar, a clip member on the forming bar adapted to hold a strand of hair wound thereon and guide the strand of hair in the winding operation, a clip turning member including a sleeve adapted to receive the forming bar, means separably coupling the clip member and the sleeve, a screw fixed in the sleeve, and a ball clutch member adapted to be reciprocated on the screw to impart rotary motion to the same and to the sleeve and clip when the clutch member 50 is moved outwardly from the screw, said clip member having a pair of spring arms spaced from the forming bar, one of said arms longer than the other.

6. A hair waving apparatus including a forming bar, a clip member on the forming bar adapted to hold a strand of hair wound thereon and guide the strand of hair in the winding operation, a clip turning member including a sleeve adapted to receive the forming bar, means separably coupling the clip member and the sleeve, a screw fixed in the sleeve, and a ball clutch member adapted to be reciprocated on the screw to impart rotary motion to the same and to the sleeve and clip when the clutch member is moved 65 70 75

outwardly from the screw, said clip member having a pair of spring arms spaced from the forming bar, one of said arms longer than the other, a base member adapted to be positioned 5 against the head of the person operated upon and clamp the forming bar therein with a strand of hair against the forming bar, said base member having a notch therein receiving the end of the longer spring arm.

10 7. A hair waving apparatus including a forming bar, a clip member on the forming bar adapted to hold a strand of hair wound thereon and guide the strand of hair in the winding operation, a clip turning member including a sleeve 15 adapted to receive the forming bar, means separably coupling the clip member and the sleeve, a screw fixed in the sleeve, and a ball clutch member adapted to be reciprocated on the screw to impart rotary motion to the same and to the 20 sleeve and clip when the clutch member is moved outwardly from the screw, said clip member having a pair of spring arms spaced from the forming bar, one of said arms longer than the other, a base member adapted to be positioned against 25 the head of the person operated upon and clamp the forming bar therein with a strand of hair against the forming bar, said base member hav-

ing a notch therein receiving the end of the longer spring arm, said longer spring arm having a beveled lower end permitting the same to ride out of the notch when the clip member is turned in the proper direction, and said forming bar having an enlarged outer end preventing removal of the clip member over said enlarged end.

8. A hair waving apparatus including a base member having a notch therein, a forming bar 10 adapted to be clamped in the base with a strand of hair clamped against the forming bar, a clip member sliding on the bar, a pair of spring arms 15 on the clip member adapted to engage the strand of hair wound on the bar, one of said spring arms longer than the other and adapted to enter the notch in the base to temporarily hold the clip member against turning, a clip turning device including a sleeve mounted to move on the bar, means coupling the sleeve to the clip member, 20 a screw fixed to the sleeve, a ball clutch member mounted to reciprocate on the screw to transmit rotary motion to the screw when moved in one direction only, a swiveled cap on the end of the screw, and finger receiving arms on the clutch 25 member.
